US00D670167S

(12) **United States Design Patent**
Winter et al.

(10) **Patent No.:** US D670,167 S
(45) **Date of Patent:** ** Nov. 6, 2012

(54) **CONTAINER WITH CAP**

(75) Inventors: **Jon Winter**, Cranfield (GB); **Chris Rogers**, Banbury (GB); **Adrian Jahina**, Olney (GB)

(73) Assignee: **Rexam Beverage Can Europe Limited**, Luton (GB)

(**) Term: **14 Years**

(21) Appl. No.: **29/381,381**

(22) Filed: **Dec. 17, 2010**

(30) **Foreign Application Priority Data**

Jun. 17, 2010 (EM) 001721192-0004

(51) **LOC (9) CL.** **09-01**

(52) **U.S. CL.** **D9/503; D9/452; D9/764**

(58) **Field of Classification Search** D9/500, D9/512-505, 516, 537, 539, 544-545, 549, D9/558, 574-575, 763-764, 772, 438, 443, D9/452; 215/379, 382-384; 220/660, 662, 220/669, 675, 569, 906

See application file for complete search history.

(57) **CLAIM**

We claim the ornamental design for a container with cap, as shown and described, the bottom of which is plain and unadorned.

DESCRIPTION

FIG. 1 is a bottom perspective view of a container with cap according to the present invention;

FIG. 2 is a side elevation view thereof;

FIG. 3 is a top plan view thereof; and,

FIG. 4 is a bottom plan view thereof.

1 Claim, 2 Drawing Sheets

US D670,167 S
